(57) **CLAIM**

The ornamental design for a communications headset, as shown and described.

DESCRIPTION

FIG. 1 is a front right perspective view of a communications headset resting in a cradle, the communications headset being shown with an earloop attached thereto. The broken line drawings of the earloop and the cradle in the drawings herein are for illustrative purposes only and form no part of the claimed design.

FIG. 2 is a front left perspective view of the communications headset with the earloop attached thereto.

FIG. 3 is a rear right perspective view of the communications headset with the earloop attached thereto.

FIG. 4 is a rear right perspective view of the communications headset.

FIG. 5 is a front elevational view of the communications headset.

FIG. 6 is a right side elevational view of the communications headset, the left side elevational view of the communications headset being a mirror image thereof.

FIG. 7 is a rear elevational view of the communications headset.

FIG. 8 is a top plan view of the communications headset; and,

FIG. 9 is a bottom plan view of the communications headset.
